UNITED STATES PATENT OFFICE.

FREDERICK W. HOEFER, OF FLORENCE, ILLINOIS.

WHIFFLETREE-CLIP.

SPECIFICATION forming part of Letters Patent No. 379,869, dated March 20, 1888.

Application filed July 25, 1887. Serial No. 245,167. (No model.)

To all whom it may concern:

Be it known that I, FREDERICK W. HOEFER, a resident of Florence, in the county of Stephenson and State of Illinois, have invented certain new and useful Improvements 5 in Whiffletree Attachments; and I do hereby declare the following to be a full, clear, and exact description of the invention, such as will enable others skilled in the art to which it pertains to make and use the same.

The invention is shown in the accompanying drawings, wherein—

Figure 1 shows the middle portion of a whiffletree with my devices in place thereon. 15 Fig. 2 shows the same seen in the direction of the arrow of Fig. 1, one portion of the device displaced. Fig. 3 is a view, partly in section, looking in the same direction as on Fig. 2. Figs. 4, 5 show, separately, the rings 20 of Fig. 1.

In all the drawings, A is the body of the whiffletree, having about its middle portion the open ferrule B, with which is formed integrally a ring, C, for attaching it to a clevis 25 or chain. The ring is provided with a depression in its upper surface, in which fits a second ring, D, which is intended to receive all the wear of the clevis or chain. The ring shown in Fig. 2 as in position to drop into the 30 depression in the ring C just fills the depression when in place and is retained by bending over its edge two or more of a series of lugs, E, rising near its edge from the surface of the outer ring. As shown at F, Fig. 3, the inner 35 diameter of the ring D is less than that of the ring C, and it may therefore be readily driven out of the depression from below if the force applied be sufficient to break or straighten the bent lugs. It is thus driven out when materially weakened by wearing at the point G 40 and turned horizontally through angular space occupied by one of the equal curves of its crenated outer margin and replaced in the depression. Other lugs may then be in like 45 manner bent over its edge to retain it until wear makes another like change desirable. The lugs are shown as double the number of sides of the ring D, and therefore two lugs may be removed at each change of position above 50 described; but in actual use this is not necessary usually, for as both the ring and its seat are slightly conical one side of the ring may be driven out without materially injuring the diametrically-opposite lug. In practice, too,

the lugs may be made very short, since, both 55 lugs and ring being of metal, the slightest projection over the ring's edge retains it with sufficient security against accidental blows—the only force tending to displace it.

The ring D may evidently be of different 60 forms—*e. g.*, a regular hexagon, or a dodecagon with equal sides and alternate angles re-entrant, and it will still possess nearly the same strength and durability and will be equivalent in operation. The ferrule B is formed of two 65 similar lips, B' B'', which may be varied in curvature to fit the middle of any whiffletree. When these lips have been drawn closely against the wood, nails, screws, or rivets are inserted through the apertures I I', Fig. 1, 70 firmly securing the whole upon the whiffletree.

The entire device, except the ring D, is formed from malleable iron or similar material in substantially the form shown and requires no fitting whatever.

The ring D may be of iron or steel and somewhat harder than the remainder of the device.

What I desire to secure by Letters Patent is set forth in the following claims:

1. The combination of the ring C, having an annular depression of regular but non-circular outline in one of its sides, the ring D, adapted to fit into said depression, and the lugs E, adapted to be bent over the ring D and retain 85 it in position, substantially as and for the purpose set forth.

2. The combination, with the body of a whiffletree, of a ring adapted for attaching the whiffletree to a chain or clevis and having integrally-formed wings or hooks B, bent oppositely about said body, substantially as set forth.

3. The combination, with the body of a whiffletree, of the perforated hooks B' B'', the 95 ring C, formed integrally with said hooks, the ring D, adapted to fit a regular non-circular depression in the ring C, and the retaining-lugs E, substantially as shown and described, for the purpose set forth.

In testimony whereof I have signed this specification in the presence of two subscribing witnesses.

FREDERICK W. HOEFER.
